(57) **CLAIM**

The ornamental design for a hand-operable face cleansing apparatus, as shown and described.

DESCRIPTION

FIG. 1 is a front elevational view of a hand-operable face cleansing apparatus showing my new design;

FIG. 2 is a rear elevational view thereof;

FIG. 3 is a side elevational view thereof;

FIG. 4 is a top plan view thereof;

FIG. 5 is a bottom plan view thereof; and,

FIG. 6 is a bottom plan view thereof showing a sponge cover attached to the showerhead.

The broken line showing of a sponge cover is included for the purpose of illustrating environmental structure and forms no part of the claimed design.
